SHOWER BATH APPARATUS

Yrjö Pajari, Montreal, Quebec, Canada

Application June 26, 1934, Serial No. 732,519

9 Claims. (Cl. 4—145)

This invention relates to certain new and useful improvements in shower bath apparatus.

The primary object of the invention is to provide shower bath apparatus embodying a shower ring that may be vertically adjustable to present the same at the desired height for the person using the apparatus and involving a foot operated release valve for the flow of water, leaving the hands free for washing purposes, the valve being of the tensioned type and automatically closing upon the release of foot pressure therefrom.

A further object of the invention is to provide shower bath apparatus of the foregoing character whereby the flow of water through a shower ring is controlled by a foot operated normally closed tensioned valve and embodying a manually operable valve for regulating the quantity or pressure flow of water.

A still further object of the invention is to provide a hingedly mounted shower ring in a shower bath apparatus that embodies a valve structure in its hinge mounting so that when the shower ring is perpendicularly disposed in inoperative position, water is prevented from flowing therethrough.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a front elevational view of a shower bath apparatus constructed in accordance with the present invention, the spray or shower ring being illustrated in perpendicular dotted line position and the bath tub being fragmentarily illustrated in section;

Figure 2 is a side elevational view of the shower bath apparatus with the shower ring and water supply pipe attached thereto illustrated in its lowered dotted line position, the wall structure and tub being shown in section;

Figure 3 is a fragmentary detail sectional view of the pressure control valve;

Figure 4 is a fragmentary detail sectional view showing the valved hinge mounting for the shower ring; and

Figure 5 is a fragmentary detail sectional view showing the manually controlled tub faucet or tap and the foot operated valve associated therewith.

The shower bath apparatus comprises a perpendicular pipe formed of upper and lower sec-

tions 10 and 11 connected together at their adjacent ends by means of the internal nipple 12 shown in Fig. 4, the pipe sections 10 and 11 being attached to the bath room or other wall 13 by means of brackets 14 as shown in Figures 2 and 3 with the lower end of the lower pipe section 11 disposed above the bath tub 15 or other receptacle.

As shown more clearly in Figures 2 and 5, the faucet or tap 16 is connected to the lower end 10 of the pipe section 11 and is in communication with hot and cold water supply pipes under control of the valves 17 and 18 as shown in Figure 1, the tap 16 carrying a wall plate 19 overlying the connection. An outlet nozzle 20 is carried by the tap 16 above the tub 15 and is provided with a valve seat 21 closed by a valve 22 under control of the manually operable valve stem 23. When the valve 22 is removed from its seat 21, water flows directly through the tap 16 and nozzle 20 for discharge into the tub 15, the mixture of hot and cold water being regulated by the wall supported valves 17 and 18.

The means for controlling the supply of water to the shower bath element of the apparatus comprises a foot operated valve within the tap 16 and as shown in Figure 5, a valve seat 24 is interposed between the tap 16 and the lower end of the pipe section 11 that is normally closed by the valve 25 normally influenced toward the seat 24 by the coil spring 26 that surrounds the depending valve stem 27 projecting downwardly through a depending tubular extension 28 carried by the tap 16. The valve rod 27 is slideable in a water tight bearing 29 that prevents the escape of water through the lower side of the tap. Diametrically opposite slots 30 are formed in the extension 28 and are traversed by a lever 31 that is pivotally mounted as at 32 to the lower end of the valve stem 27, one projecting end of the lever 31 carrying a chain 33 provided upon its lower end with a link 34 disposed adjacent the bottom of the tub 15. The valve spring 26 normally holds the lever 31 in its upward position and upon a downward pull upon the chain 33 for lowering the extended end of the lever 31, the opposite end of the lever fulcrums upon the upper wall of the adjacent extension slot 30 for unseating the valve 25 and permitting water to flow upwardly into the lower end of the pipe section 11.

The upper pipe section 10 is longitudinally slotted at its outer side as at 35 and a hollow block 36 has a cylindrical side portion 37 vertically slideable in the pipe section 10 with a reduced portion of the hollow block 36 projecting through the

guide slots 35. A cylindrical portion 38 is carried by the hollow block 36 outwardly of the pipe section 10 and houses a rotatable valve 39 operated by the handle 40 for controlling communication between the two cylindrical portions 37 and 38 of the block. As shown more clearly in Figs. 3 and 4, the pipe 41 of smaller diameter than the pipe sections 10 and 11 is arranged concentrically of the latter and is attached at its upper end to the 10 tubular portion 37 of the hollow block 36 while the lower end of the pipe 41 is provided with a plurality of packing rings 42 wiping over the inner face of the pipe sections 10 and 11 for restricting the flow of water from the tap 16 through the 15 pipe 41.

A pipe 43 depends from the cylindrical portion 38 of the hollow block 36 and the pressure of water flowing downwardly therethrough is regulated by the valve 39, the lower end of the pipe 20 43 being in communication with an upstanding nipple 44 rising from a valve casing block 45 in which a perforated spray or shower ring 46 is hingedly supported as shown in Figure 4, a valve opening 47 forms communication between the 25 lower end of the pipe 43 and the shower ring 46, this valve opening 47 being closed when the shower ring 46 is in the elevated dotted line positions shown in Figures 1 and 2. The valve casing block 45 is supported on the vertical pipe sections 30 10 and 11 by means of a slide collar 48 shown in Figure 2.

In the operation of the shower bath apparatus, water may flow directly through the nozzle 20 by removing the valve 22 from its seat 21 in the tap 16, the temperature of the water being controlled by the hot and cold water valves 17 and 18. When it is desired to use the shower ring 46, the valve 25 is removed from its seat 24 against the tension of the spring 26 by operating the lever 31 40 through the medium of the chain 33 and link 34, water then flowing upwardly through the hollow block 36 with the pressure thereof regulated by the valve 39 and then downwardly through the pipe 43 under control of the valve opening 47 to the shower ring 46. The shower ring is vertically 45 adjustable by movement of the hollow block 36 within the upper pipe section 10, lowering movement thereof being aided by the weighted block 49 resting upon the hollow block 36, the lower end 50 of the pipe 43 and shower ring 46 being guided in its movement by the slide collar 48 on the pipe sections 10 and 11.

From the above detailed description of the invention, it is believed that the construction and 55 operation thereof will at once be apparent and while there is herein shown and described the preferred embodiment of the invention, it is nevertheless to be understood that minor changes may be made therein without departing from the spirit and scope of the invention as claimed.

I claim:—

1. In shower bath apparatus, a perpendicular pipe adapted for mounting on a wall adjacent a bath tub, a manually operated valved tap at the 65 lower end of the pipe, a hollow block vertically slideable in the pipe and carrying two depending pipe sections respectively interiorly and exteriorly of the first named pipe, a shower ring at the lower end of the exterior pipe, and a foot operated valve in the tap controlling flow of water to the interior pipe.

2. In shower bath apparatus, a perpendicular pipe adapted for mounting on a wall adjacent a bath tub, a manually operated valved tap at the 75 lower end of the pipe, a hollow block vertically

slidable in the pipe and carrying two depending pipe sections respectively interiorly and exteriorly of the first named pipe, a shower ring at the lower end of the exterior pipe, a foot operated valve in the tap controlling flow of water to the interior pipe, and means carried by the block for regulating the pressure of water flowing to the shower ring.

3. In shower bath apparatus, a perpendicular pipe longitudinally slotted adjacent its upper end, a manually operated valved tap at the lower end of the pipe, a hollow block vertically slideable in the pipe and having cylindrical portions respectively interiorly and exteriorly of the pipe and a reduced intermediate portion extending through the pipe slot, a pipe depending from each cylindrical portion, packing rings at the lower end of the interior pipe to form a water tight connection with the first named pipe, a foot operated valve in the tap controlling flow of water to the interior pipe, and a shower ring at the lower end of the exterior pipe.

4. In shower bath apparatus, a perpendicular pipe longitudinally slotted adjacent its upper end, a manually operated valved tap at the lower end of the pipe, a hollow block vertically slideable in the pipe and having cylindrical portions respectively interiorly and exteriorly of the pipe and a reduced intermediate portion extending through the pipe slot, a pipe depending from each cylindrical portion, packing rings at the lower end of the interior pipe to form a water tight connection with the first named pipe, a foot operated valve in the tap controlling flow of water to the interior pipe, a shower ring at the lower end of the exterior pipe, and means carried by the block for regulating the pressure of water flowing to the shower ring.

5. In shower bath apparatus, a perpendicular pipe longitudinally slotted adjacent its upper end, a manually operated valved tap at the lower end of the pipe, a hollow block vertically slideable in the pipe and having cylindrical portions respectively interiorly and exteriorly of the pipe and a reduced intermediate portion extending through the pipe slot, a pipe depending from each cylindrical portion, packing rings at the lower end of the interior pipe to form a water tight connection with the first named pipe, a foot operated valve in the tap controlling flow of water to the interior pipe, a shower ring at the lower end of the exterior pipe, means carried by the block for regulating the pressure of water flowing to the shower ring, and a weight member on the hollow block to aid in lowering movement thereof.

6. In shower bath apparatus, a perpendicular pipe longitudinally slotted adjacent its upper end, a manually operated valved tap at the lower end of the pipe, a hollow block vertically slideable in the pipe and having cylindrical portions respectively interiorly and exteriorly of the pipe and a reduced intermediate portion extending through the pipe slot, a pipe depending from each cylindrical portion, packing rings at the lower end of the interior pipe to form a water tight connection with the first named pipe, a foot operated valve in the tap controlling flow of water to the interior pipe, a shower ring at the lower end of the exterior pipe, the shower ring being hingedly mounted at the lower end of the exterior pipe, and a valve in the hinge mounting to close the supply of water to the shower ring when the latter is swung upwardly into inoperative position.

7. In shower bath apparatus, a perpendicular pipe longitudinally slotted adjacent its upper end,

5 a manually operated valved tap at the lower end of the pipe, a hollow block vertically slidable in the pipe and having cylindrical portions respectively interiorly and exteriorly of the pipe and a reduced intermediate portion extending through the pipe slot, a pipe depending from each cylindrical portion, packing rings at the lower end of the interior pipe to form a water tight connection with the first named pipe, a foot operated valve 10 in the tap controlling flow of water to the interior pipe, a shower ring at the lower end of the exterior pipe, means carried by the block for regulating the pressure of water flowing to the shower ring, the shower ring being hingedly mounted at the lower end of the exterior pipe, and a valve in the hinge 15 mounting to close the supply of water to the shower ring when the latter is swung upwardly into inoperative position.

20 8. In shower bath apparatus, a perpendicular pipe, a tap at the lower end thereof, water supply means in communication with the tap, independ-

ently operable valves for respectively controlling the flow of water through the tap and upwardly through the pipe, a hollow block slidable in the pipe and having a valved extension exteriorly of the pipe, means in the pipe and carried by the block for directing water through the hollow block, and a shower ring in communication with the valved extension and slidable on the pipe. 5

9. In shower bath apparatus, a perpendicular pipe, a tap at the lower end thereof, water supply 10 means in communication with the tap, independently operable valves for respectively controlling the flow of water through the tap and upwardly through the pipe, a hollow block slidable in the pipe and having a valved extension exteriorly of 15 the pipe, means in the pipe and carried by the block for directing water through the hollow block, a shower ring in communication with the valved extension and slidable on the pipe, and a valved hinge mounting for the shower ring. 20
